UNITED STATES PATENT OFFICE.

CHARLES E. BROUILLETTE, OF WOONSOCKET, RHODE ISLAND.

BARBER'S IMPLEMENT.

SPECIFICATION forming part of Letters Patent No. 716,623, dated December 23, 1902.

Application filed September 30, 1902. Serial No. 125,450. (No model.)

To all whom it may concern:

Be it known that I, CHARLES E. BROUILLETTE, a citizen of the United States, residing at Woonsocket, in the county of Providence 5 and State of Rhode Island, have invented new and useful Improvements in Barbers' Implements, of which the following is a specification.

My invention consists in a compound barber's implement the novelty, utility, and practical advantages of which will be fully understood from the following description and claims when taken in connection with the accompanying drawings, in which—

15 Figure 1 is a perspective view of my improved implement as it appears when opened; Fig. 2, an enlarged longitudinal section of the same, and Fig. 3 a transverse section taken in the plane indicated by the line 3 3 of Fig. 2. 20 Similar letters of reference designate corresponding parts in all of the figures of the drawings.

In the preferred embodiment of my invention the compound implement comprises a handle A, a knife-blade B, a needle-holder C, a needle D arranged in the holder, and pincer members E E. The handle is, by preference, similar in general construction to that of a pocket-knife—*i. e.*, comprises sides a a, 25 a longitudinal central partition b, back springs c c, and a transverse pin d, the latter for the connection of the knife-blade B and the needle-holder C, which are adapted to be swung into and out of the handle against the action 30 of the back springs in the manner common to pocket-knife blades. Said handle, however, is peculiar in that it is provided in its sides with recesses or grooves e, Fig. 1, and at its end remote from the needle-holder and 35 knife-blade with a transverse shaft f, having ends g of angular form in cross-section. It is also peculiar in that a finger-nail file h, which I prefer to employ, is arranged on one of its sides a, as shown in Fig. 1.

40 The needle-holder C is provided adjacent to the pin d with an abutment i for the blunt end of the needle D, and is also provided with inner and outer needle-bearings j k and with a set-screw l, the latter being arranged in the 45 bearing j in a position to engage the needle, as shown. In virtue of this construction it will be observed that the needle is removably

secured in the holder C, and hence may be readily removed and replaced with a larger or a smaller needle, as necessity demands. 55

The pincer members E E, which are formed of steel or other suitable metal and are resilient, are mounted on the angular ends g of the shaft f and have their free ends turned inwardly, as indicated by m. Said pincer 60 members in virtue of being fixed to a common shaft must be swung out and in in concert, and it will be observed that when they are swung inwardly—*i. e.*, to positions at opposite sides of and parallel to the handle— 65 their inturned ends m will spring into the recesses e in the handle sides and hold them against casual movement.

The implement described is adapted to be carried in the pocket after the manner of a 70 pocket-knife and will be found very useful by barbers, since the pincers are adapted to extract ingrowing hairs on the face, while the needle D may be used to advantage for prick- 75 ing pimples and the like. The knife-blade B and the nail-file h adapt the implement for use in manicuring and are advantageous for such reason. I do not desire, however, to be understood as confining myself to the use of the knife-blade and nail-file, as either or both 80 may be omitted without involving a departure from the scope of my invention.

Notwithstanding its advantages as pointed out in the foregoing it will be observed that my improved implement may be produced al- 85 most, if not quite, as cheaply as an ordinary pocket-knife of corresponding size.

I have entered into a detailed description of the construction and relative arrangement of the parts embraced in the present and pre- 90 ferred embodiment of my invention in order to impart a full, clear, and exact understanding of the same. I do not desire, however, to be understood as confining myself to such construction and arrangement of parts, as 95 such changes or modifications may be made in practice as fairly fall within the scope of my claims.

Having described my invention, what I claim, and desire to secure by Letters Patent, 100 is—

1. A barber's implement, comprising a handle having exterior recesses in its opposite sides, and resilient pincer members, disposed

at opposite sides of and outside the handle, and pivotally connected to the handle adjacent to one end thereof; said pincer members having inwardly-turned free ends arranged 5 to enter the recesses in the sides of the handle, as and for the purpose described.

2. A compound implement comprising a hollow handle having back springs, recesses *e* in its sides, and a finger-nail file on one of 10 its sides, a knife-blade and a needle-holder pivotally connected to the handle at one end thereof and arranged to be swung in and out of the handle against the action of the back springs, a needle secured in and movable with 15 said holder, a transverse shaft journaled in the handle adjacent to the end thereof remote from the knife-blade and needle-holder, and having ends of angular form in cross-section, and resilient pincer members mounted on the 20 angular ends of the shaft and having their free ends turned inwardly.

3. An implement comprising a hollow handle having a back spring, a needle-holder pivotally connected to the handle so as to be 25

swung into and out of the handle against the 25 action of the spring, and having the abutment *i* and the inner and outer bearings *j k*, a needle removably arranged in said bearings and against the abutment of the holder, and a set-screw arranged in one of the bearings 30 in a position to engage the needle.

4. An implement comprising a handle having recesses *e* in its sides, a transverse shaft journaled in the handle, and having ends of angular form in cross-section, and resilient 35 pincer members mounted on the angular ends of the shaft, and having their free ends turned inwardly, and arranged to seat in the recesses *e* when the members are swung alongside the handle. 40

In testimony whereof I have hereunto set my hand in presence of two subscribing witnesses.

CHARLES E. BROUILLETTE.
